THROTTLE CONTROL FOR TWO-STAGE CARBURETOR

Harold A. Carlson, Brentwood, Mo., assignor, by mesne assignments, to ACF Industries, Incorporated, New York, N. Y., a corporation of New Jersey

Application March 29, 1954, Serial No. 419,381

3 Claims. (Cl. 261—23)

This invention relates to multi-stage carburetion systems for internal combustion engines and consists more particularly in novel means for causing opening of the secondary throttle valve at the proper time and firm closing of this valve when the primary throttle valve is closed.

There has been difficulty in the designing of multi-stage carburetors in insuring firm closing of the secondary throttle during idling, so as to minimize leakage around the valves, without undesirably increasing resistance to opening the secondary throttle either automatically or manually in response to opening of the primary throttle.

In the currently popular four barrel carburetors the ill effects of excessive air leakage at idle, which may be caused by sticking throttle valves, becomes a serious problem.

Where the secondary throttles are opened by a suction motor which responds to suction variations in the primary induction conduit, the secondary throttles may be closed by linkage connecting the same to the primary throttles, as in Ericson et al. Patent No. 2,269,930 or Bicknell Patent No. 2,640,472. A copending application Serial No. 410,299, filed February 15, 1954, in the name of the present inventor and another as joint inventors suggests a resilient connection between the throttles for firmly closing the secondary throttle.

In the present invention, the above difficulty is overcome by exposing the pressure side of the secondary throttle operating suction motor, during idle, to the high suction existing in the intake manifold whereby the motor exerts a strong closing force upon the secondary throttles.

In the accompanying drawings which illustrate the invention,

Fig. 1 is a side view of a two-stage carburetor embodying the invention, portions being removed and others broken away and sectioned for clearer illustration.

Fig. 2 is a side view of the lower portion of the carburetor.

Fig. 3 is a view similar to Fig. 2, but showing the primary throttle valve opened sufficiently so that opening of the secondary throttle valve is initiated.

Fig. 4 is a view similar to Figs. 2 and 3, but showing both throttle valves fully opened.

The carburetor shown has primary and secondary mixture conduits 6 and 7 with venturi tube arrangements 8 and 9. These primary conduits may be duplicated, as is the case in four-barrel carburetors now in use. Main fuel nozzles 10 or 11 discharge, respectively, into the primary and secondary venturi arrangements and these communicate with fuel bowl portions 12 and 13 through metering orifice elements 14 and 15. Fuel for idling is supplied through passages 16 and 17 discharging through ports 18 and 19 adjacent and posterior to primary and secondary throttle valves 20 and 21 when closed. These fuel systems supply fuel through the idling ports when their associated throttle valves are closed or nearly closed, and through the main fuel nozzles when the throttle valves are opened, the discharges from the interconnected

main and idling systems blending during opening movement of the throttle valves, as is well known. A suitable accelerating pump (not shown) may be provided.

For starting, a choke valve 25 is provided in the air inlet portion of primary intake conduit 6 and controlled by suitable automatic choke control mechanism located in housing 26 mounted on the outside of the air inlet or air horn portion of the carburetor. Fuel is supplied to constant level bowl portions 12 and 13 through the usual threaded inlet 27. Primary throttle valve 20 is manually controllable by means of a lever 28 having an aperture 29 in the free end thereof for connection by the usual linkage to the accelerator pedal located in the driver's compartment. A throttle return spring is indicated at 30 for causing closing of the primary throttle valve when the accelerator pedal is released by the operator. The closed, normal idling position of the primary throttle is determined by means of an adjustable stop screw 31 mounted on the side of the lower, throttle body portion 20 of the carburetor and an arm 32 forming a portion of throttle operating arm 28.

Secondary throttle valve 21 is operated by a suction motor including a diaphragm 35 clamped between housing portions 36 and 37 to form differential pressure chambers 38 and 39 on opposite sides thereof (Fig. 1). Casing portion 36 is shown formed integrally with the lower throttle body portion of the carburetor and includes a double-walled structure 40 forming a linkage chamber 41 into which one end of secondary throttle valve shaft 30 extends. An arm 43 rigid with shaft 42 within chamber 41 is connected by a link 44 to an actuating rod 45 centrally secured to diaphragm 35 by means of washers 46. Motor chamber 38 is connected by a passage 47, chamber 41, and a connecting passage 48 to the outlet portion of primary mixture conduit 6 posterior to throttle valve 20 therein. Chamber 41, in practice, is sealed by a cover 49 (Figs. 2, 3, and 4) secured to wall 40 by means of screws 50.

The other motor chamber 39 is connected by means of a suction passage 54 to venturi arrangement 8 in the primary mixture conduit, in this case, to the throat portion of the larger of the two venturi tubes shown.

Secondary throttle shaft 42 extends through linkage chamber 41 and is journaled in cover 49 thereon and at its extremity rigidly mounts an operating lever 55 adjustably secured in position on the shaft by bolt 56. Lever 55 has an arm 57 cooperating with adjusting screw 58 received in fixed rib 59 to determine the idling position of secondary throttle valve disk 21. A coiled tension spring 50 connects a lug 61 on secondary throttle shaft arm 55 and an arm 62 on primary throttle shaft arm 28 for urging the secondary throttle valve closed variably in accordance with the position of the primary throttle valve.

In operation, during idling, the outlet portion of primary intake conduit 6 will be exposed to relatively high suction, while Venturi tube arrangement 8 will be exposed to a much higher pressure, substantially atmospheric, except during starting when choke valve 25 is closed, so as to cause the suction motor to apply firm closing force to secondary throttle valve 21 through two way linkage 45, 44, 43. This force is supplemented by tension spring 60 which is at its greatest stress when both throttle valves are closed, as shown in Fig. 2. As primary throttle valve 20 is opened and the speed of the associated engine increased, the suction in intake conduit 6 posterior to throttle 20 and in motor chamber 38 will sharply decrease while the pressure in venturi arrangement 8 and motor chamber 39 will gradually decrease so that, ultimately, the pressure in motor chamber 39 will be sufficiently less than that in motor chamber 38 to reverse the motor action and cause secondary throttle valve to start to open, as in Fig. 3. The suction motor and its oper-

ing suction connections are calibrated so that such initiation of opening of the secondary throttle valve occurs at the desirable speed for initiating second stage operation of the carburetion system. Thereafter, during increasing speed of the engine, at normal temperature, diaphragm 35 will continue its leftward movement against spring 30, and the secondary throttle valve will continue to open and, ultimately, both throttle valves will reach their full open positions, as in Fig. 4. However, during cold starting and warmup, with the choke valve in a restricting position, there will be insufficient pressure differential in the motor chambers to cause the secondary throttle to open. When the primary throttle valve is closed and/or the speed of the engine decreases, pressure conditions in suction motor chambers 38 and 39 will approach balance and then reverse, ultimately, causing firm closing of the secondary throttle valve and elimination of the second stage operation.

Thus, suction motor chamber 38 which is the higher pressure chamber during opening movement of the secondary throttle valve, becomes a lower pressure chamber during idling to insure firm and positive closing of the secondary throttle valve. Such closing is produced, of course, without affecting the force necessary to open the secondary throttle valve, as, for instance, by increasing the size of the suction motor, as would be the case where the secondary throttle valve is urged closed by a spring. Exclusive use of all modifications as come within the scope of the appended claims is contemplated.

I claim:

1. In a multi-stage carburetor having primary and secondary mixture conduits, venturis in said conduits, fuel nozzles in said venturis, a primary throttle having an operating shaft journaled in said primary mixture conduit, and a secondary throttle having an operating shaft journaled in said secondary mixture conduit, the combination of a suction motor for operating said secondary throttle comprising a flexible diaphragm and first and second air-tight chambers on opposite sides of the flexible diaphragm, a third air-tight chamber enclosing the journal for said secondary throttle shaft, a common wall forming a partition between said second and third chambers, and an operating shaft slidably mounted in said wall and interconnecting said diaphragm and said secondary throttle shaft, said carburetor having a suction passage extending from the venturi in said primary mixture conduit to said first air-tight chamber on one side of said diaphragm, a suction passage in said wall, and a suction passage providing for communication between said primary mixture conduit posterior of said primary throttle and said third chamber, whereby said flexible diaphragm is subject on one side to the suction in the venturi in

said primary mixture conduit and on the other side to the suction in said primary mixture conduit posterior to said primary throttle.

2. In a multi-stage carburetor having primary and secondary mixture conduits, venturis in said conduits, fuel nozzles in said venturis, a primary throttle having an operating shaft journaled in said primary mixture conduit, and a secondary throttle having an operating shaft journaled in said secondary mixture conduit, the combination of a suction motor for operating said secondary throttle comprising a movable pressure-responsive member and means providing air-tight enclosures on opposite sides of said pressure-responsive member, one end of said secondary throttle shaft extending into one of said enclosures, and means in said one enclosure interconnecting said pressure-responsive member and said one end of the secondary throttle shaft, said carburetor having a suction passage providing for communication between said primary mixture conduit posterior of said primary throttle and said one enclosure, a suction passage providing for communication between the venturi in said primary mixture conduit and the other enclosure, and spring means connected between the primary and secondary throttles for biasing the secondary throttle in closing direction with maximum force when the primary throttle is closed.

3. In a multi-stage carburetor having primary and secondary mixture conduits, venturis in said conduits, fuel nozzles in said venturis, a primary throttle having an operating shaft journaled in said primary mixture conduit, and a secondary throttle having an operating shaft journaled in said secondary mixture conduit, the combination of a suction motor for operating said secondary throttle comprising a movable pressure-responsive member and means providing air-tight enclosures on opposite sides of said pressure-responsive member, said carburetor having a suction passage providing for communication between said primary mixture conduit posterior of said primary throttle and said one enclosure, a suction passage providing for communication between the venturi in said primary mixture conduit and the other enclosure, and spring means connected between the primary and secondary throttles for biasing the secondary throttle in closing direction with maximum force when the primary throttle is closed.
